UNITED STATES PATENT OFFICE.

JOSEPH L. BOHANNAN, OF FRANKFORT, KENTUCKY.

SASH-CORD FASTENER.

SPECIFICATION forming part of Letters Patent No. 388,814, dated September 4, 1888.

Application filed March 26, 1888. Serial No. 268,571. (No model.)

To all whom it may concern:

Be it known that I, JOSEPH L. BOHANNAN, a citizen of the United States, residing at Frankfort, in the county of Franklin and State 5 of Kentucky, have invented a new and useful Improvement in Sash-Cord Attachments, of which the following is a specification.

My invention relates to improvements in sash-cord attachments; and it has for its object 10 to provide a simple, cheap, and easily-applied device, which may be attached to the sash with but little cutting of the same.

With these objects in view the invention consists in a certain novel construction and 15 arrangement of devices, substantially set forth hereinafter, and specifically pointed out in connection with the accompanying drawings, wherein—

Figure 1 is a front view, partly in section, 20 of a portion of a sash, showing the improved holder in the operative position. Fig. 2 is a longitudinal central sectional view of the holder detached from the sash. Fig. 3 is an end view of the same with the sliding plate 25 removed. Fig. 4 is a sectional view on the line *x x* of Fig. 3.

Referring by letter to the drawings, A designates a cylindrical socket, having the head B on its outer end provided with the transverse dovetailed groove C. The outer edge 30 of the socket on its upper side is provided with a notch, D, through which passes the cord E, while the knot on the end of the cord rests in the cylindrical socket. The said head 35 is provided on opposite sides with the apertures F and G, and a pin, H, is passed through the aperture F and driven into the sash to hold the socket in place. The groove in the outer side of the head is tapered, and a tapered 40 slide or plate, K, having dovetailed edges, fits in the said groove. This slide or plate covers the outer end of the socket, and is secured in place by the pin N, which passes through an aperture therein, and also through the aper-

ture G in the head, which is aligned therewith. 45 The slide is also provided in its outer side with the notch L, to enable it to be readily removed from the groove.

The improved cord-fastener is adapted, as will be evident, to be applied to the edge of a 50 sash by simply boring an auger-hole therein to receive the cylindrical socket and forming a shallow recess to receive the head.

The improved fastener possesses an advantage in the fact that, although the cord is protected from contact with the casement, it may 55 be readily removed from the sash to release the latter without detaching the socket.

Sockets for the reception of knots on the ends of sash-cords have, I am aware, been 60 heretofore employed; but it will be observed that my improved fastener remains in the sash when the latter is removed from the casement, it being only necessary (in order to remove the cord from the sash) to remove the slide in 65 the outer end of the socket. This slide is so constructed as to remain firmly in position without rattling, and it effectually protects the knot from injury by contact with the side of the casement. 70

Having described my invention, I claim—

1. In a sash-cord holder, the socket having a notch in its upper side and the slide or plate fitting over the outer end of the socket, substantially as specified. 75

2. In a sash cord holder, the socket provided with a notch, D, and having a head on its outer end provided with a dovetailed groove, and the dovetailed slide or plate fitting in the said groove, substantially as specified. 80

In testimony that I claim the foregoing as my own I have hereto affixed my signature in presence of two witnesses.

JOSEPH L. BOHANNAN.
